FIRE EXTINGUISHER

George Ennis Ferguson, Spring Valley, N. Y., assignor to Pyrene Manufacturing Company, Newark, N. J., a corporation of Delaware

Application January 9, 1936, Serial No. 58,298

10 Claims. (Cl. 169—31)

This invention relates to fire extinguishers of the type wherein the pressure medium is supplied from a cartridge containing, for example, carbon dioxide in two phases, namely, gas and liquid, which are released when the cartridge is punctured.

Although fire extinguishers of the general class above mentioned possess certain inherent advantages, they have heretofore, at least under 10 certain conditions of operation, proved objectionable when conditioned for use because of fluctuating operating pressures due to clogging of the cartridge discharge passage by solidification of the pressure medium therein incident to a drop 15 in temperature occasioned by the release of such medium and/or by the formation of ice under the chilling action of the pressure medium on fire-extinguishing liquid collected in or in the vicinity of the cartridge discharge passage.

20 An important object of the present invention is to overcome the above-mentioned objections, and to that end the invention contemplates a generally improved structure wherein a free passage at the discharge end of the cartridge is insured from the instant it is punctured until its contents have 25 been spent, the invention being herein illustrated as embodied in a structure especially adapted for use in fire extinguishers which, although normally maintained in an upright position, are operated 30 in an inverted position pursuant to the cartridge puncturing operation following which the contents of the cartridge are released while the cartridge is itself in an inverted position.

Other objects and advantages of the invention 35 will become apparent from the following description when taken in connection with the accompanying drawing, in which—

Fig. 1 is a fragmental view showing in vertical, central section a fire extinguisher embodying the 40 invention, and Fig. 2 is a similar view showing the extinguisher inverted and conditioned for use.

The invention is herein illustrated in connection with an extinguisher of the type which is normally maintained in an upright position, as 45 shown in Fig. 1, but is adapted to be operated in an inverted position, as shown in Fig. 2, pursuant to its having been conditioned for use while inverted. The extinguisher includes a container 10 which is adapted for the reception of a fire extinguishing liquid, not shown, and from which such liquid may be ejected through the usual hose and nozzle unit 11. The container is provided at its upper end with a filling opening 12 and is equipped with the usual screw-threaded neck 14, adapted 50 for the reception of a removable closure 15. The

closure 15 is formed with an upwardly extending barrel-like housing 16, within the upper end of which the outwardly flanged end of a spring housing 17 is anchored by a clamp nut 18. Carried within the housing 17, is a compression 5 spring 20, the lower end of which is supported on the inwardly flanged end of the housing and the upper end of which is adapted to engage the lower end of a sleeve 21, slideable within the clamp nut 18 and forming a part of a button-like cap 22 10 which is secured to a piercer actuating rod 24 and is formed with a flange-like skirt 25, proportioned to accommodate the upper end of the barrel-like housing 16 as when the piercer actuating rod is moved against the action of its associated compression spring. The lower end of the actuating rod 24 is formed with a disc-like head 26, the peripheral margin of which is secured to and forms a liquid and gas-tight connection with the lower end of a sylphon bellows 27, which in turn is secured at its upper end to the outwardly flanged end of the spring housing 17. Connected to the lower end of the actuating rod 24, is a cartridge piercer 28, the shank portion of which is slideable within a central opening 30 formed in the bottom member 31 of a cup-like element 32, the side wall 34 of which is provided at its upper end with an outwardly extending flange 35 which is held by a gland-like clamp nut 36 in a seated position within a screw-threaded socket 37 formed centrally in the closure 15. The shank portion 20 of the cartridge piercer 28 is provided at its lower end with a disc-like stop 38, which normally seats 25 against the bottom member 31 of the cup-like element 32.

35 From the foregoing description, reference being had particularly to the manner in which the bellows 27 is utilized in connection with the piercer actuating rod 24 and its associated elements, it will become apparent that the structure 40 is such as to provide for reciprocatory movement of the cartridge piercer from without the container 10 and is also such as to maintain (in the absence of conventional rod packings, stuffing boxes, gland nuts and the like) a perfect seal 45 between the piercer actuating rod and the closure 15 through which such rod extends.

Depending from the clamp nut 36, is a cylindrical baffle 46 which is provided at its upper end with a plurality of apertures 41 and is formed at 50 its lower end with an internally screw-threaded sleeve-like socket 42 adapted for the reception of the upper screw-threaded end of a cartridge closure C, which includes a screw plug 43, the lower end of which is secured within the neck 55

or throat of a cartridge 44, within which is sealed a pressure-generating medium such as compressed carbon dioxide. The cartridge closure C also includes a centrally disposed wire-like tube 45, the passage, not shown, of which functions as a metering aperture for the cartridge which is normally maintained closed by a diaphragm-like seal 46, adapted to be held in seated position by a gland-like clamp nut 47, having an exit aperture 48, disposed in alignment with the tube 45 and adapted to permit the piercing end of the cartridge piercer to move into seal-puncturing position, as illustrated in Fig. 2.

From the foregoing description, reference beginning had particularly to the baffle 40 in association with the cartridge closure C, it will be understood that such baffle and such closure collectively serve as a bell or air trap, when the extinguisher is inverted, within which liquid entering the bell is permitted to rise to only a limited extent due to the counter pressure which is exerted on the rising liquid by the trapped air above the liquid level within the bell, it being observed that a state of equilibrium as between the liquid pressure and the pressure exerted by the entrapped air is effected incident to a relatively slight rise of liquid within the bell, with the result that the liquid level is maintained at a very substantial distance below and well out of contact with the cartridge closure and hence at a substantial distance from the vicinity of its pre-formed apertures as well as the aperture which is formed in the cartridge seal incident to the puncturing operation.

Although the bell structure or air trap, hereinbefore described as including the baffle 40 and the cartridge closure C, serves to maintain the liquid contents of the container 10 well out of the vicinity of the apertures of the cartridge closure when the extinguisher is inverted, a further precaution is taken for a somewhat analogous purpose, namely, to prevent liquid from finding its way through the apertures 41 and thence into the vicinity of the exit aperture of the cartridge closure when the extinguisher is subjected to jolts and jostling while in an upright position; and to that end there is provided an anti-slosh baffle 50, in the form of a cylindrical skirt, which is secured at its upper end to the peripheral margin of the clamp nut 36. The baffle 50 is of a length substantially equal to the baffle 40 and extends downwardly thereabout so as to form a relatively narrow annular passage 51, access to which from the container 10 is afforded at its lower end and therefore at a substantial distance from the apertures 41. The remoteness of the apertures 41 to the point of communication afforded between the annular passage 51 and the container 10, coupled with the fact that the annular passage is relatively narrow, obviously account for the effectiveness with which the baffle structure just described is adapted to function in preventing liquid from finding its way from the container 10 into the bell chamber when the liquid content of the extinguisher is unduly disturbed as by jostling while the extinguisher is in its upright position.

Although the baffle structure, hereinbefore described as including the baffles 40 and 50, serves under all conditions to effectively prevent fire-extinguishing liquid from collecting at or in the vicinity of the exit aperture 48 and hence eliminates the possibility of ice being formed by the chilling effect of the pressure medium as it is released from the cartridge, such structure in it-

self does not prevent solidification of the liquid content of the cartridge at or in the vicinity of the apertures of the cartridge closure C when it is released from the inverted cartridge. Solidification of the pressure medium is prevented, however, by the aid of a simple metering expedient which is adapted to permit the release of never more than a definite fractional portion of the liquid content and is herein illustrated as a tube 52, one end of which is secured in the cartridge closure C in alignment with the tube 45 thereof and the other end of which is provided with a collar 54, carrying a screen 55, which overlies and serves to guard the tube passage against the entrance of such foreign particles as may be present in the cartridge. When considering the function of the screen 55, it is to be noted that any foreign particles that may find their way through the mesh of such screen will be entrapped in the space afforded between the tube 45 and lower wall-portion of the tube 52, into which latter tube the tube 45 projects a short distance.

In order that a clear understanding as to the required length of the metering tube 52 may be had, it may be well to point out that the drawing illustrates that tube in a proper relation to the depth of the liquid carbon dioxide content (at -40° F.) of a cartridge 44 which has been employed with excellent results in connection with a so-called $2\frac{1}{2}$ gallon extinguisher carrying that quantity of suitable fire extinguishing medium, for example, an anti-freeze solution such as a solution of calcium chloride in water of sufficient concentration to depress the freezing point to -40° F. The cartridge 44 herein illustrated has a volumetric capacity of approximately 203 c. c. and contains approximately 65 c. c. (which is approximately 2.5 oz. avoirdupois) of liquid carbon dioxide at -40° F. Thus it will be obvious that the liquid carbon dioxide is equal by volume to approximately one-third the volumetric capacity of the cartridge and is also equal to approximately one-half the volume of the carbon dioxide gas content of the cartridge. It is to be further observed, particular reference being had to Fig. 2, that the tube 52 terminates at such a point with relation to the level of the liquid carbon dioxide (at -40° F.) that approximately one-quarter of the liquid content of the cartridge may be expelled before the inlet end of that tube is uncovered or exposed.

Taking into account the foregoing discussion of the relation of the factors peculiar to the example herein given as a practicable embodiment of the invention, it is obvious that one skilled in the art may readily adapt it to any size of fire extinguisher. To illustrate, let it be assumed that the invention is to be adapted for use in connection with a 5-gallon extinguisher. In that event an appropriate cartridge to be employed would have a volumetric capacity of approximately 406 c. c. and would contain approximately 130 c. c. of liquid carbon dioxide at -40° F., whereas the length of the metering tube would be such with respect to the depth of the liquid carbon dioxide (at -40° F.) that approximately one-quarter of the liquid content of the cartridge would be expelled before the inlet end of that tube is uncovered or exposed.

A peculiarity, concerning the operation of the device embodying the present invention, resides in the fact that, under temperature conditions of -40° F., the approximate one-quarter of the liquid carbon dioxide content, which is expelled in liquid phase immediately following the inversion

and puncturing of the cartridge, is insufficient to lower the temperature within the metering tube or any of its communicating passages to a sufficient extent to form solid carbon dioxide. This peculiarity is attributed to the fact that even though the temperature of the fire extinguishing medium, within which the cartridge and its various associated elements are submerged, is at an operating temperature of -40° F., it is nevertheless sufficiently warm to furnish ample heat to the liquid carbon dioxide as it is released to prevent that liquid from reaching the extremely low temperature of -85° F. which is required to transform it into a solid.

Another peculiarity, concerning the operation of the device embodying the present invention, resides in the fact that the liquid carbon dioxide content, which is expelled in liquid phase, is sufficient in amount to not only quickly satisfy the needs of the fire extinguishing medium from a carbon dioxide absorption standpoint, but also is enough in excess of the amount required to satisfy the absorption needs of the fire extinguishing medium to quickly generate a desired initial operating pressure in the container.

Following the discharge of the liquid carbon dioxide in liquid phase, the operating pressure, which is initiated by reason of the fact that a portion of such liquid is transformed into a gas, is maintained sufficient, by egress of the original gas content of the cartridge and by the egress of the gas into which the remaining liquid content is transformed, to insure an excellent discharge pressure until the entire quantity of the fire extinguishing medium is expelled.

Regarding the volumetric ratio of liquid content and gas content in the sealed cartridge, which in the example given is in the order of approximately 1 to 2 under operating conditions of -40° F., it will be understood that the cartridge may be charged under such conditions as will insure that ratio at that temperature. In other words, if the volumetric capacity of a cartridge is known, it may be charged with a gas such as carbon dioxide gas, the critical temperature of which is known, under such temperature and pressure conditions as will predetermine the approximate volumetric ratio of the liquid content and gas content in the sealed cartridge at any temperature below the critical temperature of the gas employed.

Although the operation of the device embodying the present invention has been described under operating conditions of -40° F., at which time the cartridge is approximately one-third full of liquid carbon dioxide, approximately one-quarter of which is expelled in liquid phase, it will be understood that that particular temperature has been selected in the discussion of the operation because that is customarily considered to be the minimum temperature at which extinguishers of the present type are required to successfully operate. The present invention obviously makes possible successful operation at higher and at lower temperatures than the particular temperature mentioned, namely, -40° F.

Concerning the operation of the device at temperatures higher than -40° F., it is to be borne in mind that as the operating temperatures are increased above -40° F. the absorption demands of the fire extinguishing liquid are decreased, with the result that less carbon dioxide is required to satisfy the needs of the fire extinguishing medium from an absorption standpoint. It has been determined, by experiment, that as the

operating temperature is increased above -40° F. the required operating pressure is established in correspondingly shorter periods of time, and that once the operating pressure is established it is maintained ample throughout the discharge period of the extinguisher.

In adapting the invention for use at operating temperatures lower than -40° F., it is to be borne in mind that the lower the operating temperature encountered the greater the absorption factor of a given fire extinguishing medium, and with this in mind the problem may, of course, be satisfactorily met, in view of the facts herein set forth, by providing for the initial discharge of a sufficient quantity of the pressure medium, while in liquid phase and without encountering the formation of solid carbon dioxide, to quickly satisfy the needs of the fire extinguishing medium from an absorption standpoint, and by providing for the release thereafter of a sufficient quantity of the pressure medium in the form of a gas to maintain the operating pressure at a satisfactory value throughout the discharge period of the extinguisher.

Although the invention is illustrated in connection with an extinguisher of the invertible type wherein the contents of the cartridge are released in part as a liquid and in part as a gas, it may be employed with extinguishers of the non-invertible type which are adapted to operate while in an upright position, in which case the entire contents of the cartridge may be released in the form of a gas.

In the case of the invertible type of extinguisher, it becomes necessary to guard against solidification of the liquid at its point of release from the cartridge and to also there guard against the formation of ice due to the presence of moisture and the chilling action of the pressure medium at its point of release from the cartridge. Whereas, in the case of the non-invertible type of extinguisher it becomes necessary to guard only against the formation of ice, inasmuch as solidification of the cartridge content cannot take place when it is released in the form of a gas. The present invention is equally adapted for use in both of these instances, because it so functions that it not only obviates solidification of the carbon dioxide when it is released in the form of a liquid, but also prevents the formation of ice by excluding the fire extinguishing liquid from the vicinity of the exit aperture where the carbon dioxide is released in the form of either gas or liquid.

No claim is made herein to the cartridge-puncturing unit per se which includes the bellows 27 and its several cooperatively associated parts, such unit being the subject-matter of a copending application for Fire extinguishers, Serial No. 137,953, filed April 20, 1937, in the name of Fred Albert Dodelin.

Although only one form of the invention is herein shown and described, it will be understood that various changes may be made without departing from the spirit of the invention or the scope of the following claims.

What is claimed is:

1. For use in a fire extinguisher employing a liquid fire-extinguishing medium, a sealed cartridge containing a pressure medium to be released, protective means associated with the exit end of the cartridge to be punctured for excluding liquid fire-extinguishing medium from the exit end of the cartridge and for thus obviating the formation there of ice under the chilling

- action of pressure medium pursuant to the puncturing operation, said protective means including a tube-like baffle connected at one end to and forming with the exit end of the cartridge a 5 chamber adapted to communicate with the cartridge when such cartridge is punctured, said baffle being provided with an aperture remotely located with respect to the exit end of said cartridge and adapted to serve as a communicating 10 passage between the interior and exterior of said chamber.
2. For use in a fire extinguisher employing a liquid fire-extinguishing medium, a sealed cartridge containing a pressure medium to be released, protective means associated with the exit 15 end of the cartridge to be punctured for excluding liquid fire-extinguishing medium from the exit end of the cartridge and for thus obviating the formation there of ice under the chilling action 20 of pressure medium pursuant to the puncturing operation, said protective means including a tube-like baffle connected at one end to and forming with the exit end of the cartridge a chamber adapted to communicate with the cartridge 25 when such cartridge is punctured, said baffle being provided with an aperture remotely located with respect to the exit end of said cartridge and adapted to serve as a communicating passage between the interior and exterior of said 30 chamber, an anti-slosh baffle disposed in an embracing relation to the first-mentioned baffle and forming therewith a passage open at one end and communicating at its other end with said chamber by way of said aperture.
3. For use in a fire extinguisher employing a liquid fire-extinguishing medium, a sealed cartridge containing a pressure medium to be released, protective means associated with the exit 35 end of the cartridge to be punctured for excluding liquid fire-extinguishing medium from the exit end of the cartridge and for thus obviating the formation there of ice under the chilling action of pressure medium pursuant to the puncturing operation, said protective means including a tube-like baffle connected at one end to and forming with the exit end of the cartridge a chamber adapted to communicate with the cartridge when such cartridge is punctured, said baffle being provided with an aperture remotely 40 located with respect to the exit end of said cartridge and adapted to serve as a communicating passage between the interior and exterior of said chamber, an anti-slosh baffle disposed in an embracing relation to the first-mentioned baffle and forming therewith a passage open at one end and communicating at its other end with said chamber by way of said aperture, said baffles being adapted 45 to collectively serve in a fire extinguisher as an anti-slosh device when such extinguisher is in an upright position and the first-mentioned baffle being adapted to serve as a bell-type air trap when such extinguisher is in an inverted position to limit the rise of fire extinguishing liquid therein to a level well below the vicinity of the exit 50 end of the cartridge.
4. In a fire extinguisher of the cartridge type, a container for a fire extinguishing liquid, a sealed cartridge containing a pressure medium which is to be released and which at -40° F. is in both 55 gas and liquid phases, the pressure medium being in such amount that the volumetric ratio of the liquid content and gas content in the sealed cartridge is approximately in the order to 1 to 2 at -40° F., metering means rendered effective upon puncturing the cartridge under temperature 60 conditions of -40° F. to insure release of approximately one-quarter of said liquid content while in liquid phase and to insure release of the remaining pressure medium in the form of a gas.

5. In a fire extinguisher of the cartridge type, a container for a fire extinguishing liquid, a sealed cartridge containing a pressure medium which is to be released and which at -40° F. is in both 65 gas and liquid phases, the pressure medium being in such amount that the volumetric ratio of the liquid content and gas content in the sealed cartridge is approximately in the order of 1 to 2 at -40° F., metering means rendered effective upon puncturing the cartridge under temperature conditions of -40° F. to insure release of approximately one-quarter of said liquid content while in liquid phase and to insure release of the remaining pressure medium in the form of a gas, said metering means including a metering tube the inlet end of which under temperature 70 conditions of -40° F. is located at such a distance below the level of said liquid that approximately one-quarter of said liquid content is above the level of said inlet end.

6. In a fire extinguisher of the cartridge type, a container for a fire extinguishing liquid, a sealed cartridge containing a pressure medium which is to be released and which at -40° F. is in both 75 gas and liquid phases, the pressure medium being in such amount that the volumetric ratio of the liquid content and gas content in the sealed cartridge is approximately in the order of 1 to 2 at -40° F., metering means rendered effective upon puncturing the cartridge under temperature conditions of -40° F. to insure release of approximately one-quarter of said liquid content while in liquid phase and to insure release of the remaining pressure medium in the form of a gas, the volumetric capacity of said container and of said cartridge being approximately 80 in the order of 947° c. c. ($2\frac{1}{2}$ gallons) and 203 c. c.

7. In a fire extinguisher of the cartridge type, a container for a fire extinguishing liquid, a sealed cartridge containing a pressure medium which is to be released and which at -40° F. is in both 85 gas and liquid phases, the pressure medium being in such amount that the volumetric ratio of the liquid content and gas content in the sealed cartridge is approximately in the order of 1 to 2 at -40° F., metering means rendered effective upon puncturing the cartridge under temperature conditions of -40° F. to insure release of approximately one-quarter of said liquid content while in liquid phase and to insure release of the remaining pressure medium in the form of a gas, said metering means including a metering tube the inlet end of which under temperature 90 conditions of -40° F. is located at such a distance below the level of said liquid that approximately one-quarter of said liquid content is above the level of said inlet end, the volumetric capacity of said container and of said cartridge being approximately 95 in the order of 947° c. c. ($2\frac{1}{2}$ gallons) and 203 c. c.

8. In a fire extinguisher of the cartridge type, a container for a fire extinguishing liquid, a sealed cartridge containing a pressure medium which is to be released and which is in such amount that at a given temperature below its critical temperature the volumetric ratio of the liquid content to the volumetric capacity of the sealed cartridge is definite, metering means rendered effective upon puncturing the cartridge to release the contents thereof, said metering means 100

including a metering tube having an inlet end which (when an operating condition of -40° F. is encountered) is at a distance below the level of the liquid content corresponding to the approximate fractional portion of the liquid content then required to satisfy the needs (from an absorption standpoint) of the fire extinguishing liquid.

9. In a fire extinguisher of the cartridge type, 10 a container for a fire extinguishing liquid, a sealed cartridge containing a pressure medium which is to be released and which is in such amount that at a given temperature below its critical temperature the volumetric ratio of the 15 liquid content to the volumetric capacity of the sealed cartridge is definite, metering means rendered effective upon puncturing the cartridge to release the contents thereof, said metering means including a metering tube having an inlet end 20 which (when the operating temperature en-

countered is such that the inlet end of the tube is submerged) is at a distance below the level of the liquid content corresponding to the approximate fractional portion of the liquid content then required to satisfy the needs (from an 5 absorption standpoint) of the fire extinguishing liquid.

10. For use in a fire extinguisher, a sealed cartridge containing a pressure medium which at relatively low temperatures with respect to the 10 critical temperature thereof is at least in part in liquid phase, and a metering tube extending into said cartridge to such an extent that its inlet end is below the level of the liquid at such relatively low temperatures, whereby upon puncturing the 15 cartridge at such temperatures a portion of the liquid is released in liquid phase and thereafter the remainder of the pressure is released in the form of a gas.

GEORGE ENNIS FERGUSON. 20

CERTIFICATE OF CORRECTION.

Patent No. 2,118,597.

May 24, 1938.

GEORGE ENNIS FERGUSON.

It is hereby certified that error appears in the printed specification of the above numbered patent requiring correction as follows: Page 2, second column, line 8, strike out the word "definite"; page 3, first column, line 69, for "temperatures" read temperature; and that the said Letters Patent should be read with these corrections therein that the same may conform to the record of the case in the Patent Office.

Signed and sealed this 5th day of July, A. D. 1938.

(Seal)

Henry Van Arsdale,
Acting Commissioner of Patents.
